UNITED STATES PATENT OFFICE.

WILLIAM P. BETTENDORF, OF DAVENPORT, IOWA.

TRUSS-BEAM.

SPECIFICATION forming part of Letters Patent No. 620,561, dated March 7, 1899.

Application filed December 2, 1896. Serial No. 614,160. (No model.)

To all whom it may concern:

Be it known that I, WILLIAM P. BETTENDORF, a citizen of the United States, and a resident of Davenport, in the county of Scott 5 and State of Iowa, have invented certain new and useful Improvements in Truss-Beams, of which the following is a full, clear, and exact description, reference being had to the accompanying drawings and to the letters of reference marked thereon.

The object of my invention is to provide a simple truss-beam for architectural, engineering, or other structural purposes. This I accomplish by the use of commercial forms of 15 metal beams, which are so manipulated that a strong and durable truss-beam is made of one homogeneous piece of metal, substantially as hereinafter fully described and as illustrated in the drawings, in which—
20 Figure 1 is a side view of an I-beam blank from which my improved truss is made. Fig. 2 is an end view of the same. Fig. 3 is a side view of one form of my improved truss-beam. Fig. 4 is an end view of the same. Fig. 5 is 25 a side view of an I-beam broken in half and one half showing a blank and the other half a modified form of truss-beam made therefrom. Fig. 6 is an end view of the said modified form of truss-beam, and Figs. 7 and 8 30 show end views of other modifications of my invention.

In the drawings, A shows the blank from which my improved truss-beam is constructed and which consists of a section of I-beam of 35 wrought-iron or steel or other suitable metal having its ends bifurcated, so as to leave arms a a. These arms are made by cutting from the web at each end of the beam a gored or V-shaped piece of metal, so as to leave incisions the inner angles or termini of which come midway between the flanges near the center of length of the beam, so as to leave a central neutral zone b. The inner edges of the arms a may be straight from the crotch 40 of the same to their ends. I prefer, however, to have the shape of the piece of metal cut from the web of the beam such that the edges of the end portions c of the arms will be parallel with the flanges thereof.

45 In completing my invention I press the two arms a at each end of the blank equally toward each other until the edges, particularly

of their end portions, inset, and then weld said edges together, and thus make a truss-beam B, as shown in Fig. 3 of the drawings, 55 which, it is apparent, possesses the maximum resistance to tensile, compression, and shearing stress.

If desired, instead of bending both arms of the blank equally toward each other I can 60 keep one bifurcation stationary and bend the other until its edge meets the edge of said stationary arm and thereupon weld or otherwise secure them together to produce the truss-beam D. (Shown in Figs. 4 and 5.) 65

In Figs. 7 and 8 I show end views of truss E, made from channel-beams. I could make a truss of channel-beams in the same manner as hereinbefore described and as illustrated in the first six figures of the drawings. I prefer, however, to make said trusses by stamping or otherwise making a longitudinal fold e in the web of the beam, the depth of which will be graduated from the point of commencement near the center of length or neutral zone of the beam to its end, as shown in Fig. 7, and then pressing the flanges of the end portions of the beam together to compress said fold e into the shape shown in Fig. 8. 70 75 80

What I claim as new is—

1. A blank for a truss-beam consisting of a section of webbed metal of suitable length having a portion of its web at each end so displaced as to leave parts of said web on either side of said displaced portion. 85

2. A blank for a truss-beam consisting of a section of webbed metal of suitable length having a portion of its web at each end so displaced as to leave parts of said web on either side of said displaced portions in their 90 original plane.

3. A blank for a truss-beam consisting of a section of webbed plate of suitable length having a portion of its web at each end cut away and having the remaining parts of said web on each side of said cut-away portion in their original planes. 95

4. A beam having portions of its web at each end displaced and the sides of the beam conterminous with said displaced portions secured together. 100

5. A beam having portions of its web at each end cut away and the sides of the beam conterminous with said removed portions

bent toward each other until the adjacent edges of the remaining parts of the web on either side of said cut-away portions meet and are secured together.

- 5 6. A beam having isosceles angular pieces cut out of the ends of the web thereof, and the sides of the beam conterminous with said cut-away portions bent toward and secured to each other.
- 10 7. A section of webbed metal having a por-

tion of its web near each end displaced from its normal plane, and its longitudinal edges bent toward each other, whereby its end portions are reduced and gradually lessened in height as its extremities are approached.

WILLIAM P. BETTENDORF.
